ELECTRIC SWITCH

Henry M. Dressel, Chicago, Kenneth C. Allison,
Arlington Heights, and Edward J. Mastney,
Berwyn, Ill., assignors to Oak Manufacturing
Company, Chicago, Ill., a corporation of Illinois

Application April 12, 1935, Serial No. 15,960

3 Claims. (Cl. 200—11)

This invention relates to electric switches and particularly to switches for use in radio receivers, and other apparatus where minute currents and potentials are encountered.

Referring to the drawing:

Figure 1 is a sectional elevation of one form of switch along line 1—1 of Figure 3.

Figure 2 is a sectional elevation of a modified form of switch, along line 2—2 of Figure 4.

Figure 3 is a top view of the switch of Figure 1. Figure 4 is a top view of the switch of Figure 2. Figure 5 is a detail.

Referring to Figure 1, a shaft 1 passes through a metallic bushing 2, having a threaded portion 3 and a collar portion 4. Beyond collar portion 4 is a reduced mounting portion 5, on which is disposed a strip of insulating material 6 of some phenol condensate. This material may be of any shape and is here shown as generally rectangular with the short sides curvilinear at 7 and 8. It will be noted that shaft 1 passes through the center portion of strip 6 and this strip bears against collar portion 4 of bushing 2. Abutting against the other side of strip 6 and disposed around collar portion 5, is a metal washer 10. The bushing 2, strip 6 and washer 10 are maintained together, by spreading the edge 11 of collar portion 5 so that it overlies washer 10 and locks the same in place.

One end of shaft 1 is cut down to provide a substantially rectangular rotor locking section 15, as shown in Figure 3. In this instance the length of section 15 is sufficient to accommodate a metal washer 18 and a rotor 19. These two have suitable apertures punched through so that they may be locked against rotation. The free end of section 15 is then spread over at 20 to prevent the washer and rotor from slipping off the shaft.

The rotor assembly is positioned by threading shaft 1 through bushing 2. To maintain the shaft in the bushing, a circular slot 21 is provided around shaft 1 at the edge of threaded portion 3 of bushing 2. A spring ring 22 is disposed in this slot, and forms an abutment against bushing 2 to maintain the structure intact.

Rotor 19 is an elongated metal member having depending tips bent down toward strip 6. Each tip 25 preferably has the two edges curved at 26 and a wide slot 27 cut in the connecting edge. Cooperating with rotor 19 are a plurality of stator contacts 28—32 inclusive. As is indicated in Figure 3, two contacts are disposed at each end of strip 6 on the arc of a circle concentric with rotor 19. Since the contacts are

all the same, a detailed description of one will suffice. Contact 28 comprises a body portion 35 rigidly maintained on strip 6 by means of an eyelet 36. On one side of body portion 35 is a connecting portion 37 suitably apertured at 38 to which wires may be soldered. Preferably portion 37 is bent up at an angle to body portion 35. The other side of body portion 35 terminates in a bent over spring contact portion 40. The extreme tip of 40 is preferably provided at 41 the sides thereof with ears 41 bent down toward strip 6. The width of portion 40 is somewhat less than the length of slot 27 in rotor contact 19 whereby a locking or indexing action is obtained. Spring portion 40 is normally biased 42 so that it firmly presses against rotor 19.

In order to limit the rotation of member 19, washer 18 is provided with a circumferential slot 41 of predetermined angular extent. For convenience in assembly, washer 18 is shown with 20 two such slots diametrically opposite to each other so that no particular care need be exercised with washer 18. Washer 10 has projecting therefrom at opposite points fingers 42 and 43. Finger 42 is bent upwardly and extends into slot 41. Finger 43 is bent downwardly and extends through a slot 44 in strip 6 and a slot 45 in bushing 2. This last finger 43 locks strip 6 and bushing 2 together. These two fingers may be equal so that no special disposition of washer 10 is 20 necessary.

In Figures 2 and 4 a modified form of switch is shown where rotor 19' is insulated from shaft 1. The rotor locking portion 15' of the shaft is longer and accommodates washer 18, insulating washer 50, rotor 19', insulating washer 51 and metal washer 52. Rotor 19 has a large central aperture 53 stamped out to clear shaft 1. Beyond this aperture, ears 54 are stamped out and bent down. These ears 54 are adapted to engage slots 40 55 in insulating washer 50. Washer 50 is preferably cut away so that as shown in Figure 4 it lies within the boundaries of rotor 19' although of course this is not important. Rotor 19' has an apertured ear 56 connecting a wire thereto. 45

What is claimed is:

1. An electric switch comprising an insulating base having an aperture therethrough, a bushing disposed in said aperture, a shaft rotatably mounted in said bushing and having an end portion projecting beyond said base, a metallic rotor rotatively locked to said shaft at the projecting portion, said rotor consisting of a rigid elongated member having at least one downturned end with the corners rounded, and a plurality of sta- 55

- stationary contacts carried by said base, each stationary contact comprising a body portion fastened to said base, a connecting portion on the outer end of said body portion and a spring U shaped contacting portion on the inner end of said body portion, said contacting portion having its free end substantially flat with side ears bent away from said rotor and adapted to make contact between said flat portion and said bent 10 end of the rotor.
2. The switch of claim 1 wherein said rotor has a slot between the rounded corners of the bent ends, said slot being somewhat wider than the flat portion of the stationary contact whereby an 15 indexing action is obtained.

3. The structure of claim 1 wherein said bushing projects beyond said base toward the rotor side of said base, a metal washer disposed around said bushing and abutting said base, said washer being provided with a finger extending toward said rotor, a washer rotatively locked to said shaft disposed between said rotor and first washer, said second washer having a slot into which the finger of said first washer projects and being large enough so that a predetermined angular rotation of the rotor is permitted.
